(57) **CLAIM**

The ornamental design for a main body for built-in wine refrigerator, as shown and described.

DESCRIPTION

1. Main body for built-in wine refrigerator

1.1 : Perspective

1.2 : Perspective view 2

1.3 : Perspective view 3

1.4 : Perspective view 4

1.5 : Front

1.6 : Perspective view in which the claimed design is installed on a wall

The broken lines depict portions of the main body for built-in wine refrigerator that form no part of the claimed design; the dash-dotted broken lines define the boundary of the claimed design and form no part thereof; the portions of reproduction 1.6 in dash-dot-dot broken lines show environmental structure only and form no part of the claimed design; this design is for a main body for built-in refrigerator made of glass, wood, synthetic resin and metal.

1 Claim, 6 Drawing Sheets
